US0D1110866S

(12) **United States Design Patent** (10) **Patent No.:** **US D1,110,866 S**
(45) **Date of Patent:** **** Feb. 3, 2026**

(54) **METAL DETECTOR**

(71) Applicant: **Garrett Electronics, Inc.**, Garland, TX (US)

(72) Inventors: **Brent C. Weaver**, Heath, TX (US); **Anthony Tran**, Plano, TX (US); **Brandon C. Rodriguez**, Richardson, TX (US); **Matheson H. Price**, Garland, TX (US)

(73) Assignee: **Garrett Electronics, Inc.**, Garland, TX (US)

(**) Term: **15 Years**

(21) Appl. No.: **29/940,512**

(22) Filed: **May 2, 2024**

(51) LOC (15) Cl. **10-04**

(52) U.S. Cl.

(57) **CLAIM**

The ornamental design for a metal detector, as shown and described.

DESCRIPTION

FIG. 1 is a right perspective view of a metal detector according to the design;

FIG. 2 is a left perspective view thereof;

FIG. 3 is a left perspective view thereof;

FIG. 4 is a right perspective view thereof;

FIG. 5 is an enlarged right perspective view thereof;

FIG. 6 is an enlarged left perspective view thereof;

FIG. 7 is an enlarged lower right perspective view thereof;

FIG. 8 is an enlarged lower left perspective view thereof;

FIG. 9 is an enlarged left perspective view thereof;

FIG. 10 is an enlarged right perspective view thereof;

FIG. 11 is an enlarged lower left perspective view thereof;

FIG. 12 is an enlarged lower right perspective view thereof;

FIG. 13 is a bottom view thereof;

FIG. 14 is an enlarged right perspective view thereof;

FIG. 15 is an enlarged left perspective view thereof;

FIG. 16 is an enlarged lower right perspective view thereof;

FIG. 17 is an enlarged lower left perspective view thereof;

FIG. 18 is an enlarged left perspective view thereof;

FIG. 19 is an enlarged right perspective view thereof;

FIG. 20 is an enlarged lower left perspective view thereof;

FIG. 21 is an enlarged lower right perspective view thereof;

FIG. 22 is a right perspective collapsed view thereof; and,

FIG. 23 is a right perspective collapsed view thereof.

Any broken lines shown throughout these figures depict environmental subject matter only and form no part of the claimed design.

1 Claim, 23 Drawing Sheets
